W. S. JOHNSON ET AL

ELECTRIC RIVET HEATER

Filed Aug. 17, 1920

UNITED STATES PATENT OFFICE.

WILLIAM S. JOHNSON AND JOHN W. SHEFFER, OF BERWICK, PENNSYLVANIA,
ASSIGNORS TO AMERICAN CAR AND FOUNDRY COMPANY, OF ST. LOUIS,
MISSOURI, A CORPORATION OF NEW JERSEY.

ELECTRIC RIVET HEATER.

Application filed August 17, 1920. Serial No. 404,178.

To all whom it may concern:

Be it known that we, WILLIAM S. JOHNSON and JOHN W. SHEFFER, residing at Berwick, county of Columbia, and State of Pennsylvania, and being citizens of the United States, have invented certain new and useful Improvements in an Electric Rivet Heater, of which the following is a full, clear, and exact description, such as will enable others skilled in the art to which it appertains to make and to use the same, reference being had to the accompanying drawings, which illustrate the preferred form of the invention; though it is to be understood that the invention is not limited to the exact details of construction shown and described, as it is obvious that various modifications thereof within the scope of the claims will occur to persons skilled in the art.

In said drawings:

Figure 1 is a broken front elevation of our improved electric rivet heater with a primary coil and a secondary coil shown in section;

Figure 2 is an end elevation of our device;

Figure 3 is a fragmentary horizontal section taken on the line 3—3 of Fig. 1;

Figure 4 is a view of the insulation placed between the primary and secondary coils;

Figure 5 is a view in side elevation of the secondary coil detached from the core and provided with terminal electrodes or blocks designed to receive steeple head rivets of different lengths without an excessive movement of the terminal blocks; and

Figure 6 is an end view of a modified form of terminal block designed to accomplish the same purpose.

It is the object of our invention to provide an improved electric rivet heater wherein the primary and secondary coils alternate on the core and the secondary coil and the insulation form a chamber, open on but one side, to receive the rivet for heating.

It is also an object of our invention to provide an improved heater that may be readily shifted by means of a crane or derrick and which has very little projecting beyond the line of the frame and liable to damage by contact with other objects while the heater is being moved.

Other objects and advantages will be apparent from the description of the drawings

in which 1 and 2 designate flanged pressed metal side members or uprights joined by cross piece 3, secured to the side members in any suitable manner, as by riveting. Secured to the tops of the side members 1 and 2 are angle bar members, as member 4 in Fig. 1, having one flange secured to the top flanges of the side members and the other flange extending upwardly therefrom. Mounted between the members 4 is the rectangular laminated core 5, the members 4 being forced into engagement with the core 5 by the bolts 6 which pass through the members 4 and beneath the core 5 and serve to keep the laminations of the core tightly pressed together. The end portions of the core 5 are engaged by the angle bars 7 and 8, as shown in Fig. 3, the angle bars being held in engagement with the core 5, so as to hold the laminations of the core together, by means of bolts 9 and 10 which pass outside of the core, the bolts 10 also serving to secure the angle bars 7 and 8 to the angle bars 4. The U-shaped angle bar member 11 and the hoisting loops 12 have their ends adjacent to the angle bars 7 and 8 and secured thereto by the bolts 9 and 10.

Surrounding the upper horizontal portion of the core 5 are the alternately placed primary and secondary coils 13 and 14 with separators or insulation 16 between each pair of coils. The primary coils consist of unit coils of the desired number of turns of wire wound on a form and suitably wrapped and insulated before being placed on the core. The secondary comprises a number of bare copper strips joined, by arc welding, to the copper blocks 17 which serve as the electrodes and between which the rivet is placed for heating. Between the coils and the core insulating strips 15 are placed.

The upper block 17 of each secondary coil 14 is secured to the angle bar 11 by the screw threaded rod 18, the block being adjustable to different positions with respect to the bar 11 by means of the nuts 19. To each of the lower blocks 17 is secured a lug 20 to which one end of a rod 21 is pivotally connected, the other end of the rod being pivotally connected to the center of a lever 22 that is pivotally connected to a cross piece 24 at one end and provided with a pivoted foot treadle 25 at its other end. Surrounding each rod 21 is a spring

26 confined between a pin 27 passed through the rod 21 and a bracket 28 secured to the cross piece 3.

- The separators 16 are designed to insulate with respect to both heat and electricity and may comprise, as shown in Fig. 4, a rectangular body with a central rectangular opening and slots extending from the opening to the outer faces of the body.
- 10 It may be conveniently constructed by forming rectangles from sheets of a material having good heat insulating qualities as well as being an electrical insulator and joining two such rectangles by spacing or corner pieces 16 of the same material. The separators serve to electrically insulate the coils from each other and prevent the radiation of heat from the secondary coil or heated rivet to the primary coil and with the blocks 17 of the 20 secondary coils and the insulated core form a chamber, open on one side only, to receive the rivet while it is being heated, thus preventing much of the loss of heat by the rivet by radiation to the coils and core and the loss that occurs where the rivet is exposed to air currents from all directions resulting in a device that is more efficient and not subjected to a variation in its operation by varying air conditions.
- 30 Secured to the front flanges of the side members 1 and 2 adjacent their tops is the rivet trough 29 and mounted on an insulating base secured to the angle bar 11 is the main control switch 30.
- 35 In Fig. 5 there is shown an upper terminal block 17^a having the front portion of the rivet engaging surface cut away so as to form an L-shaped block providing engaging surfaces 17^c and 17^d, lying in different planes, with the engaging surface 17^c below and in back of the surface 17^d. This construction provides rivet engaging surfaces at different distances from the lower terminal block and permits of a greater 45 range in the length of the rivets that can be heated in one machine without having an excessive movement of the blocks. The same results may also be obtained as shown in Fig. 6 where both the upper and lower terminal blocks are partly cut away at one side providing the rivet engaging surfaces 17^e at one side of and closer together than the surfaces 17^f. The lower terminal blocks 50 17^b, as shown in Fig. 5, is provided with openings 17^g extending through the block and counterbored at the top to provide a contact surface for engaging steeple head rivets, the openings in the block furnishing discharge passages for any scale that 55 may be deposited on the contact surface and preventing the point of the rivet head being burned during the heating.

What we claim is:

- 60 1. In an electric rivet heater, a core, a coil on said core and means mounted on said core

and cooperating with said coil to form a chamber to receive the rivet.

2. In an electric rivet heater, a core, a coil surrounding said core and insulation adjacent said coil and forming, with said coil, a chamber to receive the rivet. 70

3. In an electric rivet heater, a core, coils surrounding said core and insulation adapted to prevent heat radiation and to cooperate with some of said coils to form chambers to receive the rivets. 75

4. In an electric rivet heater, an insulated core, primary and secondary coils surrounding said core and insulation between said coils forming chambers with said secondary coils and said core insulation to receive the rivets. 80

5. In an electric rivet heater, an insulated core, a plurality of primary coils surrounding said core, a secondary coil between said primary coils, electrodes on said secondary coil adapted to cooperate to hold a rivet and insulation between said primary and secondary coils forming a chamber with said electrodes and core insulation. 85 90

6. In an electric rivet heater, a frame, a core carried by said frame, coils surrounding said core and a U-shaped member carried by said frame and supporting said coils.

7. In an electric rivet heater, a frame, a core carried by said frame, coils surrounding said core, a control switch and a support for said coils and said switch carried by the frame. 95

8. In an electric rivet heater, a frame, a core carried by said frame, means securing said core to said frame and hoisting loops secured to said securing means. 100

9. In an electric rivet heater, a frame, a core carried by said frame, means securing said core to said frame, coils on said core, a support for said coils, hoisting loops and means joining said support and hoisting loops to said securing means. 105

10. In an electric rivet heater, a secondary coil comprising flexible copper strips and solid rivet engaging copper electrodes welded to said strips. 110

11. In an electric rivet heater, a secondary coil having electrodes, one of said electrodes being shaped to provide independent rivet engaging surfaces. 115

12. In an electric rivet heater, a secondary coil having one terminal provided with contact surfaces lying in different planes and a second terminal on said coil having distinct contact surfaces adapted to cooperate with the surfaces of the other terminal. 120

13. In an electric rivet heater, a secondary coil having terminals thereon, each of said terminals having a plurality of distinct contact surfaces. 125

14. In an electric rivet heater, a secondary coil electrode having a plurality of rivet engaging surfaces. 130

15. In an electric rivet heater, a secondary coil electrode having rivet engaging surfaces lying in different planes.
16. In an electric rivet heater, a secondary coil electrode having a plurality of parallel rivet engaging surfaces.
17. In an electric rivet heater, a secondary coil electrode having openings therein, the walls of which serve as rivet engaging openings.
18. In an electric rivet heater, a secondary coil having one terminal provided with a plurality of contact surfaces and a second electrode on said coil having perforations therein the walls of which serve as contact surfaces and cooperate with the surfaces of the first electrode to hold the rivet.

In witness whereof we have hereunto set our hands in the presence of two witnesses.

WILLIAM S. JOHNSON.

JOHN W. SHEFFER.
